BUNDLE COMPRESSOR

Vernon L. Strohm and Eugene R. Kelly, Waukegan, Ill., assignors to United States Steel Company, a corporation of New Jersey

Application October 2, 1947, Serial No. 777,572

4 Claims. (Cl. 100—31)

1

This invention relates to methods and apparatus for compressing bundles, particularly for compressing annular bundles of wire or rod prior to charging the same to a normalizing furnace and thereby increasing furnace capacity.

An object of the invention is to provide improved bundle compressing apparatus operated by fluid pressure means in which the working parts of the apparatus are situated beneath floor level and thus do not occupy needed space above the floor.

A further object of the invention is to provide improved apparatus and methods for preparing annular bundles of wire or rod for charging to a normalizing furnace, the apparatus being designed to compress one or more bundles in a vertical direction, whereby a larger number of bundles can be charged to the furnace.

A further object of the invention is to provide improved methods of increasing the capacity of wire or rod normalizing furnaces wherein the wire or rod in annular bundles is compressed preliminary to entering the furnace.

In accomplishing these and other objects of the present invention, we have provided improved details of structure, a preferred form of which is shown in the accompanying drawings, wherein:

Figure 1 is a side elevational view, partly in section, of an improved bundle compressor embodying features of the present invention;

Figure 2 is a vertical sectional view taken substantially on line II—II of Figure 1;

Figure 3 is a top plan view of the compressor;

Figure 4 is a horizontal sectional view taken substantially on line IV—IV of Figure 2; and

Figure 5 is a detailed sectional view taken substantially on line V—V of Figure 4.

Referring more in detail to the drawings:

In Figures 1 and 2 there is shown a floor section 10 beneath which are situated the working parts of the bundle compressor, designated 11. The floor section shown is immediately in front of the charging end of a wire or rod normalizing furnace, not shown, but which is adapted to receive annular bundles of wire or rod 12.

The number of bundles that may constitute a single charge is limited by the furnace height; hence, by compressing the bundles it is possible to charge a larger number.

A hydraulic or pneumatic cylinder 13 is suspended from beneath floor 10. In the construction illustrated the floor is supported on I-beams 14 and said cylinder is pivoted to a guide bracket 15 welded to the lower flange of one of said I-beams, the pivotal connection being indicated

at 16. However, it is apparent that the suspending means could be varied without departing from the invention.

A double-acting piston is carried for reciprocal movement within cylinder 13 and has a downwardly extending piston rod 17 projecting from the lower end of said cylinder. Pipes 18 and 19 are connected to the top and bottom portions of said cylinder and are connected to a suitable source of fluid, either hydraulic or pneumatic, for lowering or raising the piston and piston rod. A suitable control station having valves for applying fluid pressure to the cylinder is provided at a convenient location above floor 10.

15 A pair of vertically disposed guides 20 extend between guide bracket 15 and a base 21 therebeneath. A ram 22 is carried by the lower extremity of piston rod 17 and has vertically disposed guide plates 23 that engage guides 20 for constraining movement to a vertical path. Ram 22 includes right angularly related, horizontal cross arms 24 and 25, each of which has a plurality of longitudinally spaced apertures 26 in its outer end portion, herein illustrated as three in number, Figures 4 and 5.

20 Floor 10 has apertures 27 vertically aligned with apertures 26. A plurality of ropes or cables 28 extend between the floor and the ram and pass through apertures 26 and 27. Said ropes have bights 29 above the floor apertures which provide attaching means for bundle engaging hooks 30 and also form enlargements that prevent the ropes dropping through the floor when out of use. The lower ends of ropes 28 carry 25 weights 31 which act as stops adapted to be engaged by the lower face of ram 22 for tensioning the ropes, and which hold idle ropes beneath the floor as shown in Figures 1 and 2. It is seen that the ropes of each set are arcuately spaced about the cylinder axis, Figure 3.

30 A platform reel 32 is supported on floor 10 above the working parts 11 of the compressor, preferably with its vertical axis aligned with that of cylinder 13.

35 The operation of a bundle compressing apparatus constructed as described and methods of furnace charging involving its use are as follows:

40 With ram 22 in its uppermost position, a plurality of bundles 12 of loosely packed wire or rod are conveyed to support 32 by suitable means and deposited thereon. The number of bundles may conveniently be the maximum number that can be charged in one pile in compressed condition in the furnace.

Hooks 30 are connected to the proper set of ropes 28 corresponding most nearly with bundle diameter and engaged over the top bundle of the stack. Said ropes may be freely raised through apertures 26 and 27 until weights 31 engage the underside of the ram. This distance of free movement is sufficient to enable the hooks to be placed over the top bundle.

Fluid pressure is applied to cylinder 13 through pipe 18 above the piston. The piston, piston rod 17 and ram 22 are thereby lowered. Ropes 28 to which hooks 30 are attached are thereby pulled down and tensioned and compress bundles 12 against the floor via platform 32.

The wire or rod is thereby packed tightly in the bundles with a resulting reduction in the vertical dimension of up to 20 per cent. After the bundles are compressed, they are tied with band wire, the piston is operated upwardly, the hooks are removed from the compressed bundles, and the latter are charged to the furnace.

From the foregoing description it is apparent we have provided an improved and simplified device for compressing bundles of wire or rod. The working parts are situated in an out-of-the-way location and do not occupy needed floor space. When the bundles are compressed, the capacity of the normalizing furnace is increased by one or two bundles. Hence, there is a corresponding saving in the cost of the normalizing treatment.

While we have disclosed but a single apparatus and method, it is apparent that both may be subject to modification without departing from the invention. Therefore, we do not wish to be limited to the disclosure set forth, but only by the scope of the appended claims.

We claim:

1. An apparatus for compressing annular bundles of wire or rod comprising fluid pressure means adapted to be suspended beneath a floor and including a vertically reciprocable piston and piston rod, a plurality of arcuately spaced ropes occupying more than one plane radially of said piston rod and adapted to extend through apertures in the floor above said fluid pressure means, a ram fixed to said piston rod and having apertures in more than one radial plane corresponding to the spacing of said ropes and slidably receiving said ropes, stops on said ropes beneath said ram, and separate bundle engaging means on each of said ropes adapted to engage over the top of an annular bundle, the downward movement of said ram tensioning the ropes having their engaging means engaged with a bundle and thereby compressing the bundle.

2. An apparatus for compressing annular bundles of wire or rod comprising fluid pressure means adapted to be suspended beneath a floor and including a vertically reciprocable piston and a downwardly extending piston rod, a ram including a pair of right angularly related horizontal cross members fixed to the lower extremity of said piston rod, said cross members having apertures in their end portions, a plurality of arcuately spaced ropes adapted to extend through apertures in the floor above said fluid pressure means and slidably received through the apertures in said cross members, stops on said ropes beneath said cross members, enlarge-

ments on the upper ends of said ropes, and bundle engaging means connected to said enlargements adapted to engage over the top of an annular bundle, the downward movement of said ram tensioning the ropes having their engaging means engaged with a bundle and thereby compressing the bundle.

3. In combination with a floor, an apparatus for compressing annular bundles of wire or rod comprising fluid pressure means suspended beneath the floor and including a vertically reciprocable piston and a downwardly extending piston rod, a ram fixed to the lower extremity of said piston rod, a plurality of arcuately spaced

ropes occupying more than one plane radially of said piston rod, said ram having apertures in more than one radial plane corresponding with the spacing of said ropes slidably receiving said ropes, said floor having apertures through which said ropes extend, stops on said ropes beneath said ram, and separate bundle engaging means on each of said ropes above said floor adapted to engage over the top of a bundle, the downward movement of said ram tensioning the ropes having their engaging means engaged with a bundle and thereby compressing the bundle.

4. In combination with a floor, an apparatus for compressing annular bundles of wire or rod comprising fluid pressure means suspended beneath the floor and including a vertically reciprocable piston and a downwardly extending piston rod, a ram including a pair of right angularly related horizontal cross members fixed to the lower extremity of said piston rod, said cross

members having apertures in their end portions, said floor having arcuately spaced apertures vertically aligned with the apertures in said cross members, arcuately spaced ropes slidably extending through said aligned apertures in said cross members and floor, stops on said ropes beneath said cross members, enlargements on said ropes above said floor, and bundle engaging means connected to said enlargements adapted to engage over the top of an annular bundle, the downward movement of said ram tensioning the ropes having their engaging means engaged with a bundle and thereby compressing the bundle.
